UNITED STATES PATENT OFFICE.

WILLIAM HURST, OF WINNIPEG, MANITOBA, CANADA.

EXCAVATOR.

No. 914,142.

Specification of Letters Patent.

Patented March 2, 1909.

Application filed May 8, 1908. Serial No. 431,720.

To all whom it may concern:

Be it known that I, WILLIAM HURST, of the city of Winnipeg, in the Province of Manitoba, Canada, have invented certain new and useful Improvements in Excavators, of which the following is the specification.

My invention relates to that class of excavating machines in which a vertical weighted drop cutter, blade, or drill, is employed, where sections of earth are successively broken away from the end wall of a trench or ditch.

The objects of the invention are, firstly, to cut a ditch from frozen, hard, or baked earth, of the desired width and depth, by means of a weighted wedge-shaped drill, which can be elevated and free to drop at predetermined instants, secondly, to provide means for elevating and distributing the earth loosened by the drill, and thirdly to provide means whereby the vertical guides for the weighted drill may be adjusted vertically, the parts being arranged 25 and constructed as hereinafter more particularly described.

In making the first cut in sewers, cellars, and earth excavations, generally, in colder climates where the earth is frozen, considerable difficulty has been met with, and much time has been lost in removing the surface earth. The frozen earth will vary from about five to eight feet in the colder countries and it is for loosening and removing earth of this class that my invention particularly applies. It may be used also in clay earth where it is dry or baked, but it is unnecessary for me to enumerate here all its applications, as they will be 40 quite obvious after I have described the invention.

Figure 1 is a side elevation of my complete invention. Fig. 2 is a plan view as in Fig. 1. Fig. 3 is a front elevation as in Fig. 1, the crane having been turned to one side, and certain of the parts of lesser importance being absent from the drawing to make it appear less complicated. Fig. 4 is an enlarged detailed perspective view of the 50 weighted drill and its position in the upright guides. Fig. 5 is an enlarged detailed perspective view showing the manner in which the axles supporting the guides are secured to the guides.

55 In the drawings like characters of refer-

ence indicate corresponding parts in each figure.

1 represents a boiler and 2 an engine, both of ordinary construction, which are mounted upon a portable frame or trucks 3, the 60 wheels 4 4 of which run upon longitudinal tracks 5, laid along on the sides of the trench or ditch to be excavated.

In the construction shown in the drawings the frame of the truck consists of two 65 side beams 6 6, forward and rearward transverse connecting beams 7 7, 7' 7', and a central reinforcing beam 8, there being further short beams 9 between the transverse beams to which the trucks 3 are 70 secured.

10 are channel bar uprights serving the purpose of vertical guides or slide ways for the weighted drill as hereinafter more particularly described, such channel bars being 75 inter-connected by arch or yoke shaped bars 11, the lower one 11' of which is considerably heavier than the others as it takes a greater portion of the jar. The upper ends of the angle bars 10 are connected by a bar 12 secured to each. The forward transverse beams 7 carry tracks 13 along their inner 80 upper faces.

14 are flanged wheels arranged in pairs and adapted to operate on the tracks, being 85 supported on axles 15, which are stationary, and carry spindles on which the wheels revolve. The axles 15 are fastened by bolts 16 to blocks or plates 17 adapted to slide in the channel of the bars 10. 90

18 are set screws passing from the outer side face of the channel bars inwardly and adapted to retain the plate 17 in any desired vertically disposed position. By undoing the screws 18 and raising or lowering the 95 channel bars, then tightening the screws on the plate 17 convenient adjustment is given to the bars, and by placing the axles 15 horizontally opposite, the channels 10 are supported vertically.

19 are vertical bars arranged in sets, one at either end of the forward transverse beams 7, and 20 21 are upper horizontal channel iron beams inter-connecting the upper four ends of the uprights 19, the bars 105 20 acting as tracks for wheels 21' secured on axles 22 adjustably fastened to the channel irons 10 in the same manner as the axles 15 heretofore described. The upper and the lower sets of wheels support the channel bars 110

10 from the frame and allow of a free lateral movement.

23 are brace rods or bars extending obliquely downwardly between the rear upright 5 19 and the frame 3.

24 is a weight or iron, or such like heavy metal, having its sides grooved at 25 to slide freely vertically on the channel bars 10.

26 is the drill which has its lower end 10 sharpened and its upper end firmly embedded, screwed, or fitted and held by a pin in the lower face of the weight 24.

27 are side braces fastened to the weight and to a collar 28 on the drill.

15 The drill has a sharpened end with the side toward the engine, *i.e.*, toward the face of the cut, flat, and in a plane with the inner side of the body portion and the other face is flat and tapers downwardly and inwardly.

20 In actual practice the length of the drill from the bottom of the braces 27 to the tip is somewhere between five to eight feet, and its thickness is sufficient to withstand a very severe jar.

25 29 and 30 are friction drums supported on the same platform as that which supports the boiler and engine. These drums are of any approved type, one form of which, the "Beekman friction drum", I have found to 30 be particularly adaptable. The drums are both driven through gears by the engine 2, and are controlled by levers 28' 30', by which the operator can at will cause them to coil or wind up the cable.

35 31 is a cable or rope passing from the drum 30 upwardly to the lower pulley 32 of a double pulley block and downwardly to an eye 33 secured centrally in the upper face of the weight.

40 34 is a crane having at its upper end a pulley 35 and at its lower end extend plates 36 connected by means of a bolt 37 and a swiveled eye 38 to a beam 39 bolted centrally to the forward cross beam 7.

45 40 is a cable passing from the drum 29 to an upper pulley 41 in the double blocks aforementioned, outwardly over the pulley 35, and to the end of which are secured scissor jaws 42 more or less in the form of ice 50 tongs.

It will be understood that the double block carrying the pulleys 32, 41, is swiveled to the cross arm 12 in order to allow for centering with the drum when the drill is moved laterally across the cut.

43 is a cable connected at one end to the forward cross bar 20, and to the upper end of the crane at the other.

44 is a screw shaft carried at its ends in 60 bearings 45 extending from the uprights 19 and on which operate arms 46 bolted to the rear side of the vertical channel irons 10.

47 is a pulley carried by the screw shaft and inter-connected by a belt 48 to a pulley 65 49, keyed on a shaft 50, bolted to a counter

shaft 51 carried in journals supported on the platform carrying the engine and the drums.

52 is a shaft operated by the drum 30, and 53 is the male member of a set of friction clutches feathered on the shaft.

54 is a male clutch free to rotate on the shaft, the said clutch engaging through a loose gear with a gear 55 keyed on the shaft 51. 56 is a second male clutch loose on the shaft 52 and geared through an idler 57 with 75 a gear 58 keyed on the shaft 51. 59 is a lever controlling the movement of the female clutch 53. The object of these clutches and gears is to allow of a single lever controlled for a forward or reverse rotation of the shaft 80 44, and although I have shown one method by which this may be provided for, other forms quite as adaptable may be used.

A slight outline of the operation of the mechanism as used is this:—By throwing the 85 lever 59 to the right the female member of the clutch engages with the male member 54, which through the adjoining gears rotates the shaft 51, and consequently the screw shaft 44. With the clutch in this position 90 and operating, the gear 56 is running loose or free on the shaft, being turned by the gears 57 and 58. Throwing the lever to the alternative position gives the reverse rotation to the shaft 44, and the operation of the gears 95 is obvious, being simply the reverse to that already described.

Although I have not shown in the drawings any means for moving the frame on the track some simple connections may be used 100 for rotating either set of trucks 4, the power being supplied by the engine and controlled by the lever.

An outline of the operation of the machine is as follows.—The lever 30' is thrown so the 105 cable is wound on the drum and this raises the weight together with the drill; when it has reached a sufficient height above the ground as determined by the operator the drum is released and the weight with the 110 drill drops, due to gravity. The drill enters the earth, splitting it, the solid cakes tending to drop forwardly in the cut. Successive strokes of the drill, as the screw shaft 44 moves it transversely, makes the complete 115 cut across the sewer. When the drill has passed completely across, the drill supporting frame is moved backwardly and the reverse operation is commenced, in this manner breaking forwardly and backwardly. 120 Concurrent with the breaking away of the earth it is lifted and swung to the side by means of the crane 34 operated by the lever 29'.

In places where the ground is undulating 125 provision, as hereinbefore explained, is made whereby the channel irons 10 may be adjusted vertically. Referring to Fig. 3 the position of the channel irons is that for level ground. If between the tracks the ground 130

fall away it is obvious, that in order to make a complete stroke, it will be necessary that the channel irons forming the guides will have to be dropped to make up for such 5 slight deviation.

What I claim as my invention is:

1. In an excavator the combination with the main frame supported by trucks and having a lateral track thereon, of a forward 10 framework supporting a second lateral track, of a pair of vertical uprights carried by trucks operating on the tracks, a weighted drill slideable between the uprights, and means for operating the drill, as and for the 15 purpose specified.

2. In an excavator the combination with the main frame and a framework erected forwardly thereon, the main frame and the framework both carrying laterally extending

tracks, of a set of channel bar uprights interconnected by cross arms, trucks operating on the tracks, above and below, and means whereby the channel bar uprights may be adjusted vertically with respect to the truck axles, as and for the purpose specified. 20

3. In an excavator the combination with the vertically movable weighted drill slideable in a pair of uprights vertically and horizontally adjustable, of a derrick carried by the frame supporting the uprights and adapted 25 30 for the removal of material loosened by the drill, as and for the purpose specified.

Signed at Winnipeg, in the Province of Manitoba, this 15th day of April, 1908.

WILLIAM HURST.
